has been disclaimed

Int. Cl. D6—04

U.S. Cl. D6—167

FIG. 1

FIG. 2

FIG. 4

FIG. 3

FIG. 6

FIG. 5

FIG. 1 is a perspective view of a file unit or similar article showing my new design;

FIG. 2 is an elevational view taken from one side thereof;

FIG. 3 is an end elevational view thereof;

FIG. 4 is an elevational view taken from the side opposite of that shown in FIG. 2;

FIG. 5 is an end elevational view taken from the end opposite of that shown in FIG. 3; and

FIG. 6 is a top plan view thereof.

I claim:

The ornamental design for a file unit or similar article, as shown.
